NOISE REDUCING ENCLOSURE FOR A THREAD POINTER OR THE LIKE

Richard T. Wheeler, 20 Hemlock Drive,
Vernon, Conn. 06066

Filed Feb. 28, 1974, Ser. No. 446,817

Term of patent 14 years

Int. Cl. D25—99

U.S. Cl. D25—1

FIG. 1

FIG. 2

FIG. 3

FIG. 4

FIG. 5

FIG. 6

FIG. 1 is a front, top and right side perspective view of a noise reducing enclosure for a thread pointer or the like showing my new design;

FIG. 2 is a front elevational view;

FIG. 3 is a rear elevational view;

FIG. 4 is a top plan view;

FIG. 5 is a left side elevational view;

FIG. 6 is a right side elevational view.

I claim:

The ornamental design for a noise reducing enclosure for a thread pointer or the like, as shown and described.
